[57] CLAIM

The ornamental design for a combined bottle and closure, as shown and described.

DESCRIPTION

FIG. 1 is a perspective view of a combined bottle and closure in a first position showing my new design;
FIG. 2 is a side elevational view of the combined bottle and closure, taken of the right hand side of FIG. 1;
FIG. 3 is a rear elevational view thereof;
FIG. 4 is a front elevational view thereof;
FIG. 5 is a side elevational view of the combined bottle and closure taken at the left hand side of FIG. 1;
FIG. 6 is a top plan view of the combined bottle and closure;
FIG. 7 is a bottom plan view thereof;
FIG. 8 is a top, rear and right side perspective view of the combined bottle and closure shown with the closure in an alternate position;
FIG. 9 is a side elevational view of the combined bottle and closure, taken at the right hand side of FIG. 8;
FIG. 10 is a rear elevational view thereof;
FIG. 11 is a front elevational view;
FIG. 12 is a side elevational view of the combined bottle and closure taken at the left hand side of FIG. 8;
FIG. 13 is a top plan view of the combined bottle and closure; and,
FIG. 14 is a bottom plan view thereof.
